UNITED STATES PATENT OFFICE.

THOMAS BOOKER, OF HAMILTON, CANADA.

BOTTLE-CRATE.

SPECIFICATION forming part of Letters Patent No. 657,390, dated September 4, 1900.

Application filed July 28, 1900. Serial No. 25,139. (No model.)

To all whom it may concern:

Be it known that I, THOMAS BOOKER, a subject of the Queen of Great Britain, residing at Hamilton, in the Province of Ontario and 5 Dominion of Canada, have invented certain new and useful Improvements in Bottle-Crates; and I do declare the following to be a full, clear, and exact description of the invention, such as will enable others skilled in 10 the art to which it appertains to make and use the same.

My invention relates to improvements in crates for shipping bottles, jugs, and the like, and has for its object to provide a shipping or 15 packing box or crate having upper and lower compartments to receive and embrace the bottles, said compartments being adjustable to receive bottles of different sizes and heights and effectively connected and braced to obviate liability of breakage of the bottles while 20 in transit.

With this and other minor objects in view the invention consists of certain novel features of construction, combination, and arrangement of parts, as will be hereinafter more 25 fully described, and particularly pointed out in the appended claim.

In the accompanying drawings hereto annexed and forming a part of this specification, Figure 1 is a top plan view of a box or 30 crate constructed in accordance with my invention. Fig. 2 is a longitudinal section thereof. Fig. 3 is a cross-section. Fig. 4 is a perspective view of the compartment-frames 35 detached. Fig. 5 is an end view thereof.

The box or crate comprises in its organization an outer containing-case and upper and lower compartment-frames arranged therein, each compartment-frame consisting of a series of horizontal parallel rods, a series of slats 40 slidably mounted on said rods, so as to be adjusted to form therewith the spaces or compartments to receive the body portions of the bottles, and uprights adjustably connected to the projecting ends of rods on the upper and lower compartment-frames to brace and hold the same in proper relation, the construction being such that the upper compartment-frame may be raised and lowered to 45 adapt the device for receiving bottles of different heights and the compartments of each

frame adjusted to receive bottles of different sizes.

The numeral 1 in the drawings represents the outer containing-case, which may be of 55 any approved size and is of rectangular form. In this case are placed the upper and lower compartment-frames 2 and 3, each comprising a series of horizontal parallel rods 4 and a series of vertically-disposed slats 5, provided 60 at regular intervals with orifices 6, whereby they are mounted transversely on the rods to slide toward and from each other and form, with the said rods, a series of spaces or compartments 7 to receive the bottles, 65 which spaces or compartments may be varied in size to correspond to the size of the bottle, jug, or like container to be packed or shipped by adjusting the slats on the rods in a manner readily understood. The spaces 70 or compartments of the lower compartment-frame are designed to receive the lower ends of the body portions of the bottles and the spaces or compartments of the upper frame the upper ends of the body portions of the 75 bottles just below the necks, whereby the bottles may be securely held in position and prevented from moving and becoming chipped or broken while in transit. The rods 4 are of such length as to bear against the end 80 walls of the box or case 1 and the slats 2 of the proper length to bear against the side walls thereof, whereby lateral shifting of the parts of the upper and lower compartment-frames is obviated. The slats are held from 85 shifting from their proper positions on the rods by tacks, set-screws, or other suitable fastening devices 5*.

The compartment-frames are securely braced and connected by uprights 8, four in 90 number, which are arranged in pairs at the ends of the frames and are provided adjacent to their upper and lower ends with a series of orifices 9, whereby they are adapted to be fitted upon the projecting ends of some of the rods 4 95 to support the upper compartment-frame, and thereby maintain the two frames in proper relation. By means of the series of orifices 9 the uprights are adapted to adjustably connect the two compartment-frames, so that the 100 position of the lower frame relative to the bottom of the case and the position of the

upper frame relative to said lower frame may be varied, as desired, to suit different heights of bottles.

In packing the case or crate for storage or shipment it will be understood that the bottles are inserted from above down into the coinciding spaces or compartments of the two frames, the bottoms of the bottles resting on the bottom of the case 1. By this construction a simple and effective container is provided, whereby bottles of different sizes and heights may be shipped or transported from place to place without liability of breakage or other casual injury.

Having thus described my invention, what I claim, and desire to secure by Letters Patent, is—

In a crate for shipping bottles, jugs and the like, the combination, with an inclosing box

or casing, of upper and lower interior compartment-frames each comprising a series of parallel horizontal rods, a series of parallel slats adjustably mounted on said rods and forming therewith compartments to receive bottles, means for adjustably securing the slats to the rods, and uprights arranged at the ends of the frames and adapted to adjustably engage the projecting ends of the rods, whereby the compartment-frames are adjustably connected and braced, substantially as described.

In testimony whereof I have hereunto set my hand in presence of two subscribing witnesses.

THOMAS BOOKER.
